UNITED STATES PATENT OFFICE.

JOHN PRIMROSE, OF NEW YORK, N. Y.

SUPERHEATER.

1,076,315.

Specification of Letters Patent.

Patented Oct. 21, 1913.

Application filed July 10, 1912. Serial No. 708,602.

To all whom it may concern:

Be it known that I, JOHN PRIMROSE, a subject of the King of Great Britain, residing at New York, in the county and State 5 of New York, have invented certain new and useful Improvements in Superheaters, of which the following is a full, clear, and exact description.

The invention which forms the subject 10 matter of this application relates to a novel form of superheater for boilers.

In order to obtain the highest efficiency in 15 a superheater it is necessary to provide for a certain amount of flexibility between the different parts, to employ means for draining the superheater when desired and to make the arrangement such that the headers and the superheating elements can be readily cleaned.

20 The principal objects of this invention therefore are to secure greater flexibility by employing separate inlet and outlet headers; to effectively drain the entire superheater by providing a distributing header at the bottom to which a drain pipe may be readily connected; and to effect a more efficient 25 cleaning of the superheater by employing straight elements between the inlet and outlet headers on the one hand and the distributing header or headers on the other. In this connection it may be stated that in using straight elements the amount of space occupied in the boiler is substantially less than that occupied by U-bends while at the same 30 time the area of the superheating surface is maintained at a maximum.

In addition my invention also contemplates the use of a plurality of distributing headers at the bottom whereby not only the 35 features above are attained but makes it possible to connect the bottom headers with superheating elements in order to increase the efficiency as a superheater.

40 Other objects and advantages of the invention will appear from the description below taken in connection with the accompanying drawings wherein is shown the preferred embodiments of the invention and in which,

45 Figure 1 is a cross-section of a sterilizing boiler to which my superheater has been applied. Fig. 2 is a section showing the distributing header at the lower end of the superheating elements. Figs. 3 and 4 are 50 views similar to Figs. 1 and 2 but showing a construction wherein two distributing head-

ers are utilized at the bottom and connected to each other by U-bends.

Referring to the drawings in detail, and in particular Figs. 1 and 2, the reference 55 character 10 designates a boiler setting of usual construction provided with a plurality of upper drums 11, 12 and 13 and with a lower or mud drum 14 the former being connected to the latter by banks of tubes as 60 shown at 15, 16 and 17. The said drums are preferably arranged transversely of the boiler setting. Connecting the drums 11 and 12 is a plurality of circulating tubes 18. These circulating tubes are divided as shown 65 and located above the lower set. The baffle 19 may be utilized to protect the inlet and outlet headers 20 and 21 from the extreme heat at this point to which they would otherwise be subjected. The inlet headers are 70 connected to the steam space of the drum 12 by means of the pipe 22. Circulating tubes 23, similar to circulating tubes 18, are employed to connect the drums 12 and 13.

As before stated the inlet and outlet 75 headers 20 and 21 are located above the baffle 19 and to these headers are connected one of the ends of superheating elements 24, 25 respectively, while the lower ends of these elements are connected to a common or continuous distributing or return header 26. It will 80 therefore be apparent from the construction just described that straight superheating elements 24 and 25 can be used exclusively 85 in lieu of the U-shaped elements now in 90 vogue. These straight elements not only permit the same to be more readily cleaned which is a distinct advantage over the bent tubes, but also allows the use of a distributor connected thereto to afford draining 95 means for the superheater. Another important feature of the construction is the fact that greater flexibility is attained.

Referring to the modified form shown in 100 Figs. 3 and 4 it will be noted that I employ one inlet and one outlet at the top and a plurality of distributing headers 26 at the bottom. It will be apparent that the advantages accruing from the arrangement shown in Figs. 1 and 2 are obtained also in the 105 modified form shown in Figs. 3 and 4. In addition I provide auxiliary superheater elements 27 which materially increase the heating surface of the superheater upon which the degree of superheat depends, and also 110 increases the travel of the steam, at the same time breaking up the currents of steam pass-

ing through the superheater and thereby insuring a better mixture and a more uniform superheat. As shown the cast iron protection if used is omitted from the superheater elements where they pass between the boiler tubes, as indicated at 28. The drain for the lower distributing header or headers is indicated at 29.

It is to be understood that I make no claim 10 to the boiler setting *per se*, but simply chose the specific construction shown with a view to elucidate the principles of my invention in combination with one specific type of boiler; and it is to be understood that minor 15 details as to the construction and design may be resorted to in connection with the superheater without departing from the true spirit and scope as defined by the appended claims.

20 What I claim is:

1. In combination with a boiler, a superheater comprising separate inlet and outlet headers located at the top for the admission and discharge of steam and arranged transversely of the said boiler, one of said headers located in front of the other as regards the passage of gases through the furnace, a distributing header at the lower end of said superheater of substantially the same 25 length as said inlet and outlet headers, a row of superheating elements connecting the inlet header at the upper end thereof with the distributing header at the lower end, and separate superheating elements for 30 connecting the distributing header and the outlet header one row of said elements being located in front of the other and the individual superheating elements of each row connected to the distributing header adjacent to 35 each other.

2. In combination with a boiler, a superheater comprising an inlet header at the top for the admission of steam to be superheated, a distributing header at the lower 45 end thereof, substantially straight superheating elements connecting the said headers and adapted to convey the steam from the upper header to the distributing header, an outlet or discharge header for the superheated steam at the upper end thereof, and 50 superheating elements connecting the last mentioned header with the distributing header and adapted to convey the steam from the distributing header to the said out-

let header, one of said group of superheating elements being located in front of the other and the individual superheating elements of each row connected to the distributing header adjacent to each other.

3. A superheater comprising separate inlet and outlet headers arranged substantially parallel and located one in front of the other as regards the passage of gases therethrough, a plurality of distributing headers at the lower end thereof similarly arranged, substantially straight superheating elements for connecting the inlet header with one of the distributing headers, substantially straight superheating elements for connecting the outlet header with the other distributing header, and superheating tubes for connecting the distributing headers.

4: A superheater comprising separate inlet and outlet headers at the upper end thereof, a plurality of distributing headers at the lower end thereof, superheating elements for connecting the inlet header with one of said distributing headers and for connecting the outlet header with another of said distributing headers, and superheating elements connecting said distributing headers.

5. In a superheater comprising inlet and outlet headers at the upper end thereof separated from each other to allow for flexibility, a plurality of distributing headers at the lower end thereof having tubes connected thereto for draining the superheater, superheater elements connecting the upper and lower headers, and auxiliary superheaters connecting said distributing headers.

6. In combination with a boiler having a plurality of drums, circulating tubes connecting said drums and a superheater comprising inlet and outlet headers located above said circulating tubes, substantially straight superheating elements connected to said headers and passing downwardly between said tubes, and a distributing or return header at the lower end of said elements.

In testimony whereof I affix my signature in the presence of two subscribing witnesses.

JOHN PRIMROSE.
